SMOKING PIPE

August Pasut, Detroit, Mich.

Application November 26, 1942, Serial No. 466,997

2 Claims. (Cl. 131—201)

The present invention relates to tobacco smoking pipes and specifically to pipes designed to separate from the smoke any and all liquid substances such as tars, water and other materials distilled from the tobacco, and to likewise trap and remove saliva from contact with the smoke.

Among the objects of the invention is a tobacco smoking pipe construction in which the smoke, in passing from the bowl, is separated from its content of easily condensable material before traveling to the pipe stem proper.

Another object is a construction in which any saliva passing into the stem is bypassed into a chamber out of the path of the smoke entering the stem.

Still another object is a pipe having large chambers for collection of the substances indicated and so arranged as to be easily and effectively cleaned.

Other objects will readily occur to those skilled in the art upon reference to the following description and the accompanying drawing in which

Figure 1 is a longitudinal central vertical section through a pipe embodying the invention.

Figure 2 is a front end view of the lower portion of the bowl with a part removed.

Figures 3 and 4 are sectional views on line 3—3 and 4—4 respectively of Figure 1.

Figure 5 is a section on line 5—5 of Figure 4.

In the drawing, the pipe is shown as consisting of a bowl 10, stem portion 11, and the removable bit 12, which latter may be inserted in the end of the stem and held in place by friction in the well known manner.

The bit 12 will be provided with the usual longitudinal passage 13 extending therethrough and with a reduced portion 14 adapted to fit within the end of the stem 11. It is also provided with a forward extension consisting of a flattened portion 15 through which extends the passage 13 and which is provided with a vertical through passage 16 intersecting with the passage 13.

The adjacent end of the stem 11 will be provided with an enlarged opening 20 into which extends the horizontal flattened portion 15 of the bit, and the latter divides the chamber 20 into an upper and lower portion.

Extending forward within the stem in the lower portion thereof, is the chamber extension 25 which serves as a space for collecting any saliva or other liquids which may find their way into the chamber 20. From the upper portion of chamber 20 a smoke passage 30 leads forward and into the upper part or ceiling of a forward chamber 31. This chamber is preferably imme-

diate below the bowl 10 and is enlarged by having it extend lengthwise of the stem 11 as indicated at 32. The forward portion of chamber 31 is provided with a removable end wall 33 which serves the purpose of closing the chamber and also permits easy cleaning of the chamber 31.

Extending from the bowl 10 into chamber 31 is a small smoke passage 35 so arranged as to direct smoke entering the chamber away from the open end of passage 30.

It will be noted that the two chambers 31 and 20 are very much larger in cross sectional area than the passages 35, 30 and 13. The effect of this is to temporarily slow down the stream of smoke in each of the two chambers. Such slowing down permits a reduction in temperature of the smoke and likewise gives the entraining vapors a chance to condense and deposit in the chambers.

As is well known in the burning of tobacco in a smoking pipe, there is considerable distillation of tars, water vapor, etc., which if allowed to pass into the smoker's mouth, produce disagreeable results. Likewise, there is usually a collection of moisture within the stem due to the condensation of some of the water vapor mentioned, which is disagreeable to the smoker.

The construction shown and described herein, however, permits the deposit of such materials in the chambers 31 and 20 and prevents their passing through the bit 12.

I am aware that the invention may be embodied in other specific forms without departing from the spirit or essential attributes thereof, and I therefore desire the present embodiment to be considered in all respects as illustrative and not restrictive; reference being had to the appended claims rather than to the foregoing description to indicate the scope of the invention.

I claim:

1. In a tobacco smoking pipe having a bowl and stem portion and a separable bit, a relatively large chamber in said stem portion beneath said bowl and having an extension into said stem, means for conducting smoke downwardly and in a forward direction from said bowl to said chamber, a smoke conduit leading from the ceiling of said chamber at a point remote from and to the rear of a vertical line from the smoke discharge of said conducting means, said conduit extending lengthwise of said stem in the upper portion thereof, a second chamber in the bit end of the stem and into which said conduit opens, 55 said second chamber having an extension into

said stem in the lower portion of the latter, and a bit provided with a centrally located smoke passage and provided with partition means dividing said second chamber horizontally, said partition having a vertical through passage intersecting the central smoke passage.

2. In a tobacco smoking pipe consisting of a bowl, stem and removable bit, a bit provided with a longitudinal smoke passage and having its forward end flattened and provided with a vertical through passage intersecting the longitudinal passage, said stem having an enlarged opening to receive said flattened end and to be thereby divided into upper and lower chambers, a smoke

passage extending lengthwise of said stem from the said upper chamber to a point adjacent the lower end of said bowl, a forward chamber below said bowl and into which said passage opens downwardly, said forward chamber and said lower chamber each having an extension in the lower part of said stem and extending lengthwise thereof, a conduit leading from the bowl to said forward chamber and opening thereinto at a point ahead of the passage opening and inclined so as to direct smoke away from the last mentioned smoke passage, and removable means constituting one wall of said forward chamber.

AUGUST PASUT.
